UNITED STATES PATENT OFFICE.

JOHN C. SCOVEL, JR., OF CHICAGO, ILLINOIS, ASSIGNOR TO THE CREAMERY PACKAGE MANUFACTURING COMPANY, OF CHICAGO, ILLINOIS, A CORPORATION OF ILLINOIS.

COMPRESSOR.

1,218,903.

Specification of Letters Patent. Patented Mar. 13, 1917.

Application filed May 17, 1916. Serial No. 98,040.

To all whom it may concern:

Be it known that I, JOHN C. SCOVEL, JR., a citizen of the United States, residing at Chicago, in the county of Cook and State of Illinois, have invented certain new and useful Improvements in Compressors, of which the following is a specification.

This invention relates to improvements in the cylinder, piston and valves of gas compressors such as are used in refrigerating systems.

One object of the invention is to provide a suction trap in the cylinder wall, the same to be interposed between the supply pipe and the inlet port.

A further object of this invention is to provide the piston with a direct passage from the inlet port to the inlet valves.

Another object of this invention is to provide the piston of the compressor with improved inlet suction valves.

In the accompanying drawings I have shown my invention as applied to a two-cylinder compressor. Figure 1 is an elevational view of a compressor with parts in section. Fig. 2 is an enlarged vertical sectional view of a portion of the piston on line 2-2 of Fig. 4. Fig. 3 is a cross-section of the piston taken on line 3-3 of Fig. 2. Fig. 4 is a similar view taken on line 4-4 of Fig. 2. Fig. 5 is a vertical sectional view on line 5-5 of Fig. 4. Fig. 6 is a cross-section of the cylinders taken on line 6-6 of Fig. 1 showing the suction trap. Fig. 7 is a vertical sectional view of the suction trap taken on line 7-7 of Fig. 6.

I will herein describe the preferred embodiment of my invention but it will be understood that I do not thereby intend to limit myself to the precise details of construction shown in the drawings, but aim to include all modification of the invention as defined in the appended claims.

In Fig. 1 I have shown a compressor comprising an inlet or supply pipe 1, cylinders 2, only one of which is visible in Fig. 1, a piston 3, an exhaust valve 4, a discharge pipe 5, a water jacket 6, and a fly-wheel 7. It is customary to provide a slot or duct in the side of the body of the piston for a gas passage from the inlet port in the cylinder wall to the suction valves in the piston head. I have provided a direct and unobstructed passage from the inlet port 8 (Figs. 6 and 7) to the suction inlet valves 9 in the

piston head 10 by forming the body of the piston of a central portion 11^a with radially disposed supporting vanes 11^b, herein shown in the shape of a cross in Figs. 1, 2 and 3. In this manner the body of the piston is enlightened considerably. It will be seen that I have replaced the customary ducted cylindrical piston with one that is lighter and more efficient.

The inlet suction valves 9 shown in Figs. 6, 2, 4 and 5, are located in the piston head 10. Herein I have shown each suction valve as comprising the valve member 12, the seat 13, the annular chamber 14 below the seat, the guides 15, the hollow cylindrical valve stem 16 and the valve ports 17 formed therein. The gas passes from the passageways of the piston through the hollow cylindrical stem, the valve ports in the stem, and the annular chamber beneath the valve to the cylinder.

From the foregoing it will be understood that the valve members 12 have a reciprocating motion which is the reverse of the piston motion. Suitable means are provided to limit this motion upon the suction stroke, as for example, pins 18 which are carried by the piston head 10 and which extend through the positioned slots 19 in the valve members 12. The pins in turn are held against endwise movement by suitable means such as by one of the piston rings 20 shown in Figs. 2, 4 and 5.

Between the cylinders 2^a and 2^b, Figs. 6 and 7, a chamber 21 is formed. A depending wall or partition 22 divides this chamber into two communicating chambers 21^a and 21^b, the former communicating with the inlet pipe 1 and the latter communicating with the ports 8 in the cylinder walls. The gas is supplied by the inlet pipe and passes successively through the chambers 21^a and 21^b, the ports 8, the piston 3 and the suction valves 9 into the cylinder. In the working cycle of the refrigerating fluid, vaporization is generally incomplete, and the returning vapor is saturated to a greater or less degree with liquid. The returning saturated vapor frequently carries scale from the piping system. When the vapor passes from the supply pipe 1 into the chamber 21 it impinges upon the depending wall 22 and the liquid and the scale are precipitated from the vapor to the wall and subsequently to the bottom of the chamber. The

vapor meanwhile passes the barrier and is supplied to the cylinder through the port opening 8. In this manner the partition 22 in chamber 21 causes the latter to act as a suction trap for the compressor, the trap shown herein being proportioned to have a volumetric capacity capable of once completely filling each cylinder.

I claim as my invention:

- 10 1. A compressor having, in combination, a cylinder having an inlet port, a piston comprising a head portion and a body portion having a central portion and a plurality of radially disposed vanes forming central angles, and inlet valves in said head portion aligned with the central angles defined by said vanes whereby a direct and unobstructed passage is provided from said port to each of said valves.
- 15 2. A compressor having, in combination, a cylinder having an inlet port, a piston comprising a head portion and a cross-shaped body portion, and inlet valves in said head portion aligned with the quadrants defined by said body portion whereby a direct and unobstructed passage is provided from said port to each of said valves.
- 20 3. A compressor having, in combination, a piston, an inlet suction valve in said piston, a pin in the piston extending loosely through said valve for limiting the reciprocatory movement of said valve, and a piston ring on said piston for holding said pin in place.
- 25 4. A compressor having, in combination, an inlet pipe, a plurality of cylinders each having an inlet port, the adjacent walls of said cylinders forming a chamber communicating with said ports and said inlet pipe, and a partition in said chamber between said cylinder ports and said inlet pipe whereby said chamber acts as a suction trap.
- 30 5. A compressor having, in combination,

a plurality of cylinders each having a port, an inlet pipe for supplying gas to said cylinders, the adjacent walls of said cylinders forming a chamber therebetween, said chamber communicating with said ports and said pipe, a piston in each of said cylinders comprising a head portion and a body portion having a central portion and a plurality of 50 radially disposed vanes, means for admitting gas from said pistons to within said cylinders, and a partition in said chamber between said inlet pipe and said ports whereby said chamber will act as a suction trap.

6. A compressor having, in combination, a piston, an inlet suction valve therein comprising a valve seat, said piston having a chamber beneath said valve seat, a valve stem guide supported by the piston beneath 60 said chamber to form the bottom wall thereof and a hollow valve stem having a head portion, ports in the wall of the stem communicating with said chamber beneath the valve seat and a complementary portion 65 slidable within said guide, a pin in the piston extending loosely through said valve for limiting the reciprocatory movement of said valve, and means for holding said pin in place on said piston.

7. A suction valve having, in combination, a valve seat, a support for said seat having a chamber beneath said seat, a valve stem guide beneath said chamber and forming the bottom wall thereof, a hollow valve stem having a head portion, ports communicating with said chamber beneath the valve seat and a complementary portion slid able within said guide, and means for limiting the reciprocatory movement of said valve 80 stem.

In testimony whereof, I have hereunto set my hand.

JOHN C. SCOVEL, JR.
